(No Model.)

W. HUGHES.

ADJUSTABLE SCREEN DOOR.

No. 374,187.

Patented Dec. 6, 1887.

UNITED STATES PATENT OFFICE.

WILLIAM HUGHES, OF MINERVA, OHIO.

ADJUSTABLE SCREEN-DOOR.

SPECIFICATION forming part of Letters Patent No. 374,187, dated December 6, 1887.

Application filed September 9, 1887. Serial No. 249,234. (No model.)

To all whom it may concern:

Be it known that I, WILLIAM HUGHES, a citizen of the United States of America, residing at Minerva, in the county of Stark and State 5 of Ohio, have invented certain new and useful Improvements in Adjustable Screen-Doors, of which the following is a specification, reference being had therein to the accompanying drawings.

10 My invention relates to screen-doors; and it has for its object to produce doors of this class which will be capable of adjustment to fit openings of various sizes.

15 The invention will first be described in connection with the accompanying drawings, and then pointed out in the claims.

Figure 1 of the drawings is a front elevation, partly in section, of a door provided with the auxiliary screen and expanded to full width. 20 Fig. 2 is a front elevation of a door without the auxiliary screen and adjusted to its narrowest limit. Fig. 3 is a vertical section of the door taken on the line $\alpha\alpha$, Fig. 1. Fig. 4 is a plan view of the auxiliary screen.

25 Referring to the drawings, A A are the side rails of the door, which are made the length of doors of the largest size common in dwellings. These rails are about four and one-half inches in width and are grooved on their inner edges, 30 as at a, to the depth of about three and one-half inches, and in these grooves are placed springs B, which press against the screen-frame, hereinafter described, and adjust it in accordance with the width of the door.

35 C C represent the cross-rails of the door, each of which is constructed in two pieces, c c', one of said pieces, c', being tongued on its inner side, as at 1, and the other, c, correspondingly grooved, as at 2. Both pieces are reduced in 40 thickness for the greater portion of their length, leaving a shoulder, 3, (seen in full and dotted lines,) where the reduction commences, so that when they are put together the cross-rail will be of one thickness throughout its length. Both 45 pieces are also rabbeted, as at 4, so that when they are together these rabbets will form a groove for the reception of the screen-frame, as clearly shown in Fig. 3. One end of each piece c and c' is tenoned to fit in groove a in 50 side rails, A, as seen in dotted lines, and is rig-

idly secured therein by screws, glue, or other suitable means. The pieces are held together adjustably by headed bolts 5 and screw-threaded nuts 6, the said bolts passing through a hole, 7, and a slot, 8, in each piece, the hole 55 in one piece registering with the slot in the other piece, as seen in full and dotted lines.

D represents the screen-frame, and E the wire-cloth screen. This frame is of just sufficient thickness to work freely in the grooves a 60 and 4 in the side rails and cross-rails, respectively, and it is of a width and length suitable for the smallest-size door in common use, as seen in Fig. 2, wherein the door is illustrated as adjusted to its narrowest limit and the side 65 rails cut off on a line with the top of the upper cross-rail.

As before stated, in the manufacture of these screen-doors I make the side rails of a length suitable for the largest doors in common use. 70 Now, when a door larger than the smallest size is required, I provide an auxiliary cross-rail, F, constructed precisely like the rails C, to each piece of which I attach a strip of wire-cloth, f, long enough to extend slightly beyond the 75 middle of said piece, so that when rail F is extended to its full width the meeting ends of these strips will slightly overlap, as seen in Fig. 1, and thus freely slide one upon the other while the rail is being adjusted to a less width, 80 as seen in Fig. 4. I secure this auxiliary rail in the grooves of the side rails at the proper height for a door of the desired length, trim off the wire-cloth at the bottom, so that its lower edge will just rest on top of the upper cross-rail C, and then, if the door is not to be of the full height of the side rails, cut the latter off on a line with the top of the auxiliary rail. The door can then be adjusted as to width in an obvious manner. 85

Having thus described my invention, what I claim, and desire to secure by Letters Patent, is—

1. The combination, with the side rails grooved on their inner edges, springs located 95 in said grooves, the two-part adjustable cross-rails rabbeted to form grooves, as specified, and bolts and nuts for adjustably securing the parts of the cross-rails together, of the screen-frame and screen, the former adapted to fit in 100

the grooves in the side rails and cross-rails and bear against the springs in the side rails, for the purpose set forth.

2. The combination, with the grooved side rails, the springs therein, the two-part adjustable grooved cross-rails, bolts and nuts for securing the parts of the cross-rails together, and the screen-frame provided with a screen, of the auxiliary adjustable two-part cross-rail, to each part of which is provided with a screen

the meeting ends of which overlap each other, the whole constructed, arranged, and operating in the manner above set forth.

In testimony whereof I affix my signature in presence of two witnesses.

WILLIAM HUGHES.

Witnesses:

JOHN F. JEROME,
P. C. RAMSEY.
